[57] CLAIM

The ornamental design for a chair, as shown and described.

DESCRIPTION

FIG. 1 is a perspective view of the chair;
FIG. 2 is a side elevational view of the chair of FIG. 1. The other side of the chair is the same as shown in this FIG. 2;
FIG. 3 is a front elevational view of the chair of FIG. 1;
FIG. 4 is a rear elevational view of the chair of FIG. 1;
FIG. 5 is a top plan view of the chair of FIG. 1; and,
FIG. 6 is an alternate embodiment of the chair of FIG. 1, wherein the chair has a taller back member, with all other views of the chair being otherwise similar to those shown in FIGS. 1-5.
